CLAIM

The ornamental design for a luggage interior having removable bag, as shown and described.

DESCRIPTION

FIG. 1 is a first isometric view of the luggage interior having removable bag of the present invention;

FIG. 2 is a second isometric view thereof;

FIG. 3 is a third isometric view thereof;

FIG. 4 is a fourth isometric view thereof;

FIG. 5 is a fifth isometric view thereof;

FIG. 6 is a sixth isometric view thereof;

FIG. 7 is seventh isometric view thereof;

FIG. 8 is a top plan thereof; and,

FIG. 9 is bottom plan view thereof.

The broken lines showing the luggage exterior illustrate portions of the article that form no part of the claimed design.
